(57) **CLAIM**

The ornamental design for a compressor, as shown and described.

DESCRIPTION

FIG. 1 is a front elevation view showing the new design; FIG. 2 is a rear elevation view thereof; FIG. 3 is a side elevation view thereof; FIG. 4 is a side elevation view thereof, showing the opposite side of FIG. 3; FIG. 5 is a top plan view thereof; and, FIG. 6 is a bottom plan view thereof. The broken lines shown in the drawings identify environmental structure or boundaries that form no part of the design to be patented.
